UNITED STATES PATENT OFFICE

2,328,822

UMBRELLA

Rupert D. Lyon, Rochester, N. Y.

Application March 29, 1943, Serial No. 481,022

4 Claims. (Cl. 135—25)

The present invention relates to new and useful improvements in umbrellas, and has for its primary object to provide, in a manner as hereinafter set forth, a device of this character comprising a novel construction and arrangement whereby the umbrella will occupy a minimum of space when it is folded and not in use.

Another very important object of the invention is to provide an umbrella of the aforementioned character comprising foldable, sectional ribs of unique construction.

Other objects of the invention are to provide a folding umbrella of the character described which will be comparatively simple in construction, strong, durable, compact, light in weight, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in vertical section through an umbrella constructed in accordance with the present invention, showing said umbrella open.

Figure 2 is an elevational view, showing the frame structure of the umbrella partially folded, a portion only of the cover being shown in vertical section.

Figure 3 is a view in horizontal section, taken substantially on the line 3—3 of Figure 1.

Figure 4 is a detail view in elevation of the tube.

Figure 5 is an elevational view of the upper end portion of the staff.

Figure 6 is a detail view in vertical section through one of the hinges which connect the rib sections.

Referring now to the drawings, in detail, it will be seen that the embodiment of the invention which has been illustrated comprises a staff 1 of wood or other suitable material. The staff 1 is provided with a knob 2 on its lower end. Mounted on the upper end portion of the staff 1 in spaced, concentric relation thereto, is a ring 3. The ring 3 is fixed on the projecting end portions of a pin 4 which is mounted diametrically in the staff 1.

A tube 5 is slidably mounted on the staff 1. The tube 5 has formed therein diametrically opposite slots 6 which accommodate the pin 4, said tube being slidable through the ring 3. An opening 7 in the lower portion of the tube 5 ac-

commmodates the latch 8 on the staff 1 for releasably securing said tube in extended position.

Mounted on the upper end portion of the tube 5 is a head 9. Ribs 10 have one end pivotally connected to the head 9. The ribs 10 comprise folding sections 11 which are pivotally connected by hinges 12. Fingers 13 of substantially segmental cross-section project from the pivotally connected ends of the sections 11 for engagement beneath the adjacent sections for supporting the ribs 10 in unfolded position when the umbrella is open. Further, the ribs 11 are offset adjacent their hinges or pivots 12, as at 14, in a manner to permit the sections 11 to parallel each other when the ribs 10 are folded.

Stays or braces 15 have one end pivotally connected to ring 3 and their other ends pivotally connected to the innermost sections 11 of the ribs 10. Retaining cords 16 from the outermost rib sections 11 are connected, as at 17, to the lower portion of the tube 5. The ribs 10 have mounted thereon a suitable cover 18. Mounted on the intermediate section of one of the ribs 10 is a tape or the like 19 to be tied around the umbrella when it is folded.

It is thought that the manner in which the umbrella functions will be readily apparent from a consideration of the foregoing. Briefly, to open the umbrella, the tube 5 is slipped forwardly or upwardly on the staff 1 in a manner to project beyond the forward or upper end of said staff, in which position said tube is secured by engagement of the latch 8 in the opening 7. When the tube 5 is thus moved forwardly or upwardly on the staff 1, the braces 15 are caused to swing outwardly to a substantially horizontal position, thereby opening the ribs 10 which are unfolded during this operation. As hereinbefore stated, the tube 5 is slidable through the ring 3 on the end portions of the pin 4 and is secured by said pin against rotation relative to the staff 1.

It is believed that the many advantages of a folding or collapsible umbrella constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

1. An umbrella comprising a staff, a tube slidably on the staff and adapted to project beyond one end thereof, ribs pivotally mounted on the

tube, said ribs comprising a plurality of foldable sections, a cover mounted on the ribs, and braces pivotally mounted on the staff and pivotally connected to the ribs.

2. A folding umbrella comprising a staff, a tube slidable on the staff, a plurality of ribs pivotally mounted on the tube, said ribs comprising a plurality of foldable sections, said sections being pivotally connected, supporting fingers on the pivoted ends of the sections engageable beneath the adjacent sections, means connecting the ribs to the staff for actuation hereby and a cover mounted on the ribs.

3. An umbrella of the character described comprising a staff, a ring mounted on one end portion of said staff in spaced, concentric relation thereto, a tube slidable on the staff, said tube extending slidably through the ring, foldable

ribs pivotally mounted on one end portion of the tube, braces pivotally connected to the ring and to the ribs, and a cover mounted on said ribs.

4. An umbrella comprising a staff, a tube slidably mounted on the staff and adapted to project beyond one end thereof, said tube having diametrically opposite, longitudinal slots therein, a head on one end portion of the tube, a plurality of foldable ribs pivotally mounted on said head, a cover mounted on the ribs, a pin mounted diametrically in one end portion of the staff, the end portions of said pin projecting through the slots in the tube, a ring mounted on the end portions of the pin and encircling the tube, and braces pivotally connected to the ring and to the ribs.
